United States Patent Office

Des. 191,064
Patented Aug. 8, 1961

191,064

VENDING MACHINE

William A. Gran, Independence, Mo., assignor to The Vendo Company, Kansas City, Mo., a corporation of Missouri

Filed Sept. 8, 1960, Ser. No. 62,059

Term of patent 14 years

(Cl. D52—3)

Fig. 1.

Fig. 2.

FIG. 1 is a perspective view of the vending machine taken from the front and one side thereof, showing my new design;

FIG. 2 is a side elevational view thereof on a reduced scale.

The undisclosed side of the vending machine is substantially the same in appearance as the side shown.

I claim:

The ornamental design for a vending machine, as shown and described.
